UNITED STATES PATENT OFFICE.

AUGUST TEGOLI, OF SANTA ROSA, CALIFORNIA, ASSIGNOR OF ONE-HALF TO CHARLES BERTOLI, OF SANTA ROSA, CALIFORNIA.

PASTE-DRIER

1,198,604.

Specification of Letters Patent. Patented Sept. 19, 1916.

Application filed August 16, 1915. Serial No. 45,686.

To all whom it may concern:

Be it known that I, AUGUST TEGOLI, a citizen of the Kingdom of Italy, residing at Santa Rosa, in the county of Sonoma and State of California, have invented certain new and useful Improvements in Paste-Driers, of which the following is a specification.

This invention relates to improvements in what may be generally termed driers, especially designed for drying "long" paste, commercially known as macaroni, and the like.

The invention has for its object to provide for effecting the drying operation with facility, expedition and economy.

A further object is to secure a product of superior quality.

A still further object is to carry out the aforesaid ends in a simple and effective manner.

The invention consists therefore of an air-blast generating means in connection with an air-heating chamber or chambers arranged for delivering or subjecting the article treated to regulated air-blasts, substantially as hereinafter more fully disclosed and defined by the appended claims.

In the accompanying drawings wherein it will be understood that various changes and modifications may be made as to the detailed construction and arrangement of parts without departing from the scope of the claims and in which drawings

Figure 1 is a longitudinal section of my invention with certain parts broken away. Fig. 2 is a horizontal section thereof with parts broken away. Figs. 3 and 4 represent sectional elevations of the same with parts broken away, respectively.

In carrying out my invention, I erect a general casing or housing 1, which may be of indefinite rectangular dimensions, as suggested by the broken away outlines, the same having built in one side thereof an air exhaust funnel or chute 2, which is in communication with a suction or exhaust generator chamber 2^a. The chute 2 extends downwardly through the floor near its outlet, as at 3^a.

The suction generator or exhaust chute 2 is provided at its upper end with the horizontal shorter and longer diverging branches or pipes 4^a and 4^b which extend into the separate heating compartments 3 and 4, re-

spectively, said heating compartments communicating with the drying chamber 5 through the transverse longitudinally spaced ports or openings 6 and 6^a in the horizontal wall or partition A separating the heating compartments and the drying chamber, said ports or openings being equipped with the hinged closures or valves 7 and 7^a. The drying chamber 5 which is situated below the heating compartments or at the bottom of the casing and extends the entire length of the latter, is arranged to receive the cars or trucks 8 carrying, in upper and lower tiers, the sticks or rods 9 upon which the "long" paste may be strung or suspended for drying, as in making macaroni, etc. The heating chambers 3 and 4 have arranged therein for heating the admitted air, the steam heated pipe coils or helices 10 and 10^a suitably supported therein in the manner shown or otherwise with their intake and out-take pipe ends extending horizontally through the partitions or side walls *a* and *b* of the heating compartments and connected to the source of steam supply and exhaust chambers thereof (not shown) as well understood. Also arranged in the heating chambers 3 and 4, preferably as shown, in separate central transverse openings *d* in the partitions or side walls *a* and *c* thereof, are air-blast generating fans 12, the blades of which are secured to a common shaft 13 journaled in suitably lubricated bearings 14 mounted upon the transverse bars or members as shown. Said shaft 13 is equipped at its outer end with fast and loose pulleys 15 and 16, respectively, and in practice, it is driven by a belt from a motor (not shown) for driving or rotating the shaft and fans in either direction as desired to change the direction of the blast from the fans, and accordingly change or reverse the direction in which the heated air travels in making a circuit through the drying chamber and heating chamber. The upper portion of the casing 1 is offset or extended at its rear end beyond the heating chambers 3 and 4, as clearly shown more particularly in Figs. 1 and 2, for providing an air circulating space 17 in the top of the casing above the drying chamber and in rear of the heating compartments 3 and 4. An air circulating space 17^a is also provided in the top of the casing above the drying chamber 5 and in front of the heating compartments, as shown.

Suitably positioned with its lower end at the bottom of the drying chamber directly below the offset or extension at the rear end of the casing above referred to, is an outwardly and upwardly inclined sliding door 18 provided at its upper end with hangers 19 equipped with the grooved traction wheels 20 traveling upon a track 21 overhanging the door for access to the interior 10 of the casing and the drying chamber 5, at the rear.

In operation, the "long" paste is suitably hung upon the "sticks" 9 as stated and the "sticks" placed in position in the trucks 8, 15 the latter when filled, being then rolled into the casing in the drying chamber 5, as shown, after which operation the casing and the drying chamber is completely closed and the valves or closures 7 and 7^a all thrown open. The fans or generators 12 are now put in motion, setting up a circulation or blast of air through the drying chamber as indicated by the arrows, any moist laden or saturated air passing out at the outlet 20 25, controlled by the valve 26. The fans 12 may be rotated in either direction to cause the heated air to make a circuit through the heating chambers and drying compartment, that is, to change or reverse the direction 30 in which the air travels or circulates through said chambers and compartments. To regulate the temperature of the air in the casing and prevent it from being heated to too great an extent, the valve 24 in the upper 35 end of the exhaust chute 2 may be opened temporarily to draw off some of the heated air through the branches or pipes 4^a and 4^b of the exhaust chute and through the latter and the exhaust chamber 2^a to the outside or 40 exterior, and the valve 23 at the upper end of the exhaust chute 2 then opened to allow a fresh quantity or supply of unheated air to enter the casing, as is apparent.

Among advantages of my invention, it reduces the time of drying about from a week 45 to a day and a half or the time may be reduced even eighteen hours if this be desired. It uses but a fraction of the space required by the employment of other methods, it prevents souring or molding, preserves the 50 original light color of the goods and avoids curling, cracking or breaking, also insures uniform drying; its capacity is about a ton of dried paste.

55 I claim—

1. A machine of the type described including a lower drying chamber adapted to receive means for supporting "long" paste as in the manufacture of macaroni, upper 60 separate communicating heating compartments provided with air-blast generators for delivery into the heating chambers, said drying chamber and heating compartments having closure controlling means therebetween for regulating the air-blast,

2. A machine of the type described including a lower drying chamber adapted to receive means for supporting "long" paste as in the manufacture of macaroni, upper 70 separate communicating heating compartments provided with air-blast generators for delivery into the heating chambers, said drying chamber and heating compartments having closure controlling means therebetween for regulating the air-blast, and steam coils 75 arranged in said heating compartments, a vertically disposed suction or exhaust chute arranged at one end of the casing and having horizontal inwardly extending branches communicating, each, with one of the heating 80 compartments.

3. A machine of the type described including a lower drying chamber adapted to receive means for supporting "long" paste as in the manufacture of macaroni, upper 85 separate communicating heating compartments provided with air-blast generators for delivery into the heating chambers, said drying chamber and heating compartments having closure controlling means therebetween for regulating the air-blast, a vertically disposed suction generator or exhaust chute arranged at one end of the casing and having a pair of shorter and longer horizontal diverging branches or pipes communicating with the respective heating compartments. 90

4. A machine of the type described including a lower drying chamber adapted to receive means for supporting "long" paste 100 as in the manufacture of macaroni, upper separate communicating heating compartments provided with air-blast generators for delivery into the heating chambers, said drying chamber and heating compartments having closure controlling means therebetween for regulating the air-blast, a vertically disposed suction generator or exhaust chute arranged at one end of the casing and having a pair of shorter and longer horizontal diverging branches or pipes communicating with the respective heating compartments. 105

110

5. A machine of the type described including a lower drying chamber adapted to receive means for supporting "long" paste as in the manufacture of macaroni, upper 115 separate communicating heating compartments provided with air-blast generators for delivery into the heating chambers, said drying chamber and heating compartments having closure controlling means therebetween for regulating the air-blast, a vertically disposed suction generator or exhaust chute arranged at one end of the casing and having a pair of shorter and longer horizontal diverging branches or pipes communicating with the respective heating compartments. 120

125

130

- parts, and steam heated coils arranged in the respective heating compartments for the purpose specified, said coils having straight horizontal intake and out-take pipe 5 ends or portions extending through the walls or partitions of the compartments and the rear wall of the casing.
6. A machine of the type described including a lower drying chamber adapted to receive means for supporting "long" paste as in the manufacture of macaroni, upper separate communicating heating compartments provided with air-blast generators for delivery into the heating chambers, said 10 drying chamber and heating compartments having closure controlling means therebetween for regulating the air-blast, a vertically disposed suction generator or exhaust chute arranged at one end of the casing and 15 having a pair of shorter and longer horizontal diverging branches or pipes communicating with the respective heating compartments, and steam heated coils arranged in the respective heating compartments for the purpose specified, said coils having straight horizontal intake and outtake pipe ends or portions extending through the walls or partitions of the compartments and the rear wall of the casing, 20 a horizontal shaft extending through the heating compartments and the steam heated helical coils on which the air blast generators or fans are mounted and means for driving or rotating the shaft.
- 25 7. A machine of the type described including a lower-drying chamber adapted to receive means for supporting "long" paste as in the manufacture of macaroni, upper separate communicating heating compartments provided with air-blast generators for delivery into the heating chambers, said 30 drying chamber and heating compartments having closures controlling means therebetween for regulating the air-blast, and steam heated coils arranged in said heating compartments, a vertically disposed suction exhaust chute arranged at one end of the casing and having horizontal inwardly extending 35 branches communicating each with one of the heating compartments, a valve adapted to close the upper end of the exhaust chute and a valve to allow ingress of a fresh quantity or supply of air to the interior of the casing, when opened.
- 40 5. 8. A machine of the character specified comprising a horizontal rectangular casing having a plurality of upper longitudinally spaced heating compartments and a lower drying chamber beneath said heating compartments, said drying chamber extending approximately the entire length and the entire width of the casing, air-blast generators or fans working in transverse openings on the outer partitions or side walls of the 45 heating compartments to cause a circulation of heated air through the drying chamber and heating means in the heating compartments, hinged closures or valves for controlling the circulation of the heated air through the drying chamber and heating means in the heating compartments, said casing having its upper end at the rear offset or extending beyond the adjacent heating compartment to provide an air circulating space in the rear of said compartments, and also having an air circulating space in its top above the drying chamber in front of said heating compartments.
- 50 9. A machine of the character specified comprising a horizontal rectangular casing having a plurality of upper longitudinally spaced heating compartments and a lower drying chamber beneath said heating compartments, said drying chamber extending approximately the entire length and the entire width of the casing, air-blast generators or fans working in transverse openings on the outer partitions or side walls of the heating compartments to cause a circulation of heated air through the drying chamber and heating compartments, said casing having its upper end at the rear offset or extending beyond the adjacent heating compartment to provide an air circulating space in the rear of said compartments, and also having an air circulating space in its top above the drying chamber in front of said heating compartments.
- 55 10. A machine of the character specified comprising a horizontal rectangular casing having a plurality of upper longitudinally spaced heating compartments and a lower drying chamber beneath said heating compartments, said drying chamber extending approximately the entire length and the entire width of the casing, air-blast generators or fans working in transverse openings on the outer partitions or side walls of the heating compartments to cause a circulation of heated air through the drying chamber and heating compartments, hinged closures or valves for controlling the circulation of the heated air through the drying chamber and heating means in the heating compartments, said casing having its upper end at the rear offset or extending beyond the adjacent heating compartment to provide an air circulating space in the rear of said compartments, and an upwardly and outwardly inclined sliding door providing for access to the interior of the drying chamber and casing at the rear.
- 60 11. A machine of the character specified comprising an approximately rectangular casing having upper longitudinally spaced heating compartments provided in their outer side walls with transverse openings and a lower drying chamber extending approximately the entire length of the casing beneath said heating compartments, air-blast generators or fans working in said transverse openings, a horizontal shaft on

which said fans are mounted, steam heated coils in the heating chambers, hinged valves for controlling the circulation of the heated air through the drying chamber, a vertically disposed suction or exhaust chute having horizontal branches at its upper end, and communicating with the respective heating chambers and a sliding door for gaining access to the interior of the drying chamber and casing, said casing having its upper

end at the rear offset or extended beyond the adjacent heating compartment to provide an air circulating space at the rear of said compartments.

In testimony whereof I affix my signature ¹⁵ in presence of two witnesses.
